UNITED STATES PATENT OFFICE.

CHARLES FISHER, OF CHICAGO, ILLINOIS, ASSIGNOR TO THE AUTOMATIC RECORDING
SAFE COMPANY, OF CHICAGO, ILLINOIS, A CORPORATION OF ILLINOIS.

SAVINGS BANK.

Application filed May 31, 1921. Serial No. 473,972.

To all whom it may concern:

Be it known that I, CHARLES FISHER, a citizen of the United States, residing at Chicago, in the county of Cook and State of Illinois, have invented a new and useful Improvement in Savings Banks, of which the following is a specification.

This invention relates particularly to savings-banks which are provided with a plurality of coin chambers adapted to maintain coins of different denominations in assorted, stacked relation.

The improved savings-bank in which the present invention is embodied is of the general construction and mode of operation set forth in my United States Patent No. 1,170,525, granted February 8, 1916. The primary object is to provide improvements in the general construction and mode of operation of the savings-bank described and claimed in said patent. Further objects are to provide improved coin-admission means and improved locking means.

The invention is illustrated in its preferred embodiment in the accompanying drawings, in which—

Fig. 1 represents a front elevational view of a savings-bank embodying the invention; Fig. 2, a plan view of a stand or support for the savings-bank which may be employed by a cashier or teller when the savings-bank is to be opened and the coins counted; Fig. 3, a rear view of the rear plate or casing-section of the device; Fig. 4, a side elevational view of the stand or support with the savings-bank resting therein, one side flange of the stand being broken away; Fig. 5, an end view of the assembly shown in Fig. 4; Fig. 6, an inner plan view of the rear or tray-section of the savings-bank; Fig. 7, a vertical section taken as indicated at line 7 of Fig. 4; Fig. 8, an inner view of the front casing-section; Fig. 9, a section taken as indicated at line 9 of Fig. 8 and showing the lower side of the inner plate which constitutes a part of the coin-admission means; Fig. 10, a section taken as indicated at line 10 of Fig. 8; Fig. 11, a section taken as indicated at line 11 of Fig. 8; Fig. 12, an

enlarged broken section taken as indicated at line 12 of Fig. 9 and illustrating one of the anchorages of the spring-wire slot-guards employed; Fig. 13, an enlarged broken section taken as indicated at lines 13 of Figs. 55 9 and 10; Fig. 14, an enlarged broken section taken as indicated at line 14 of Fig. 9; Fig. 15, a section taken as indicated at line 15 of Fig. 17, this view showing the lock mechanism mounted in the lower portion of the savings-bank; Fig. 16, a section taken as indicated at line 16 of Fig. 17; Fig. 17, an enlarged broken sectional view taken as indicated at line 17 of Fig. 15; Fig. 18, a broken view of a key employed; Fig. 19, a broken sectional view taken as indicated at line 19 of Fig. 12; Fig. 20, a broken sectional view taken as indicated at line 20 of Fig. 15; Fig. 21, a broken sectional view taken as indicated at line 21 70 of Fig. 15; Fig. 22, a broken sectional view taken as indicated at line 22 of Fig. 7; and Fig. 23, a broken sectional view taken as indicated at line 23 of Fig. 6.

In the construction illustrated, A represents the improved savings-bank; and B, a stand or support which is especially adapted to support the improved savings-bank when opened and the coins counted by a receiving teller of a banking institution.

The improved savings-bank A comprises complementary front and rear sections A' and A², respectively, the sections being substantially flat-sided equipped with cooperating locking devices for detachably securing them together. These sections are vertical sections. The rear section, because of the function it serves while the coins are being counted, may be termed a tray-section. The front section is preferably adapted to receive within its peripheral flange the tray-section, and so may be termed a cover-section when put together, the sections form a substantially flat, rectangular body, with appropriately rounded corners, where desired.

The tray-section A² preferably comprises a flat metal plate 1, which may be of cast metal, if desired. This plate is so formed on its inner side as to provide partial coin

80

85

90

95

100

compartments 2 which are complementary with respect to partial coin compartments 2^a with which the cover-section A' is provided interiorly and two corresponding partial coin compartments from a complete coin compartment when the savings-bank is closed. As shown, the coin compartments are adapted to receive coins of different denominations.

10 The plate 1 is provided on its inner surface with vertical or longitudinal flanges 1^a which separate the partial coin compartments of the tray-section from each other. The inner wall of the plate 1 is recessed or provided with longitudinal concavities as indicated at 1^b. Flanking the longitudinal concavities 1^b are plane surfaces 1^c which afford surfaces upon which the coins may slide when they are being "told off" 20 or counted by the teller.

The tray-section A² is further provided near its lower end with a transverse slot 1^d which affords a bottom wall for the coin compartments. The wall 1^d is preferably inclined at an angle of 12½° with respect to a horizontal plane, so that when the savings-bank is in standing position, the coins 3 in the coin compartments will rest on the bottom wall 1^d, but will incline somewhat with 30 respect to the axes of the coin-stacks. This will be understood from Figs. 22, but it is to be borne in mind that this figure shows the savings-bank in a horizontal position, instead of standing on end as shown in Fig. 25 22, which is the proper position when the coins are being inserted.

The bottom wall 1^d is in reality a transverse flange projecting forwardly from the plate 1 of the tray-section near the lower 40 end of said plate, this flange inclining forwardly and downwardly from the plate. Near the front edge of this flange, the metal is cut away, as indicated at 4, so as to produce a somewhat sharper inclination. When 45 the savings-bank is resting in the position shown in Fig. 22, the upper edge of the stack of coins may be pressed towards the surface 4, which is of sharper inclination, thus "fanning" the coins, or giving them a greater inclination. This is done after the cover-section 50 is removed to facilitate the work of "telling off" the coins, which may be effected by means of one forefinger, while the coins are received either on the counter or in the other hand of the teller.

The front casing-section A' is preferably stamped from brass or other sheet-metal. It comprises a bowed or concavo-convex front wall 5, lateral flanges 5^a, a top flange 5^b, and 60 a bottom flange 5^c. The rear or free edge of the top flange 5^b is equipped at its intermediate portion with a downturned interlock flange 5^d which is adapted to engage the intermediate portion of the upper rear margin of the casing-section A² at the space 65

which is afforded by the interruption of a marginal flange 7 with which the casing-section A² is equipped on its rear side (see Fig. 3).

The partial coin chambers 2^a of the front 70 casing-section are separated from each other by longitudinal division walls 5^a, as will be understood from Figs. 7 and 8. These separating walls are preferably formed from sheet-metal strips 7, each strip being bent 75 upon itself along a median longitudinal line, and the free edges of the strip being curved or bent away from each other, to afford attaching flanges 7^a which bear against the inner surface of the front wall 5 of the casing-section A'. The strips are secured to said front wall by means of integral clenching lugs 8 which are struck rearwardly from the front wall of the casing-section. These clenching lugs extend thru perforations 9 85 with which the flanges 7^a are provided and the extremities are clenched against the rear surfaces of said flanges. These clenching lugs are preferably located at the upper portion of the casing section; and the perforations in the front wall of the casing-section are covered by a name-plate 10 which is secured to the front wall of the casing-section by rivets 10^a.

The front wall 5 is provided with several 90 vertical series of perforations or slots 11 which are located in front of the vertical axes of the several coin chambers. These slots or view-openings enable the coins to be viewed. Associated with the several series of slots are series of graduations 11^a 95 which serve to indicate the number of coins in each compartment, so that the savings-bank is thus preferably of the recording, or so-called registering, safe type.

The upper flange or top wall 5^b of the casing-section A' is provided with a series of coin-slots 12 which are so disposed as to be located above the several coin chambers when the savings-bank is closed. These coin-slots are preferably disposed obliquely, as shown in Figs. 5 and 11. Secured to the top wall 5^b is an inner coin-slot-plate 13 which is separated from the top wall by a small space 13^a. The plate 13 is provided with coin-slots 12^a which register with the slots 12 (Fig. 14). At the ends of the slots 12^a the metal is struck upwardly, as indicated at 13^b, thus providing spacing lugs which are engaged by clenching lugs 5^e which are formed integrally with the upper wall 5^b of the casing-section A'. These clenching lugs are provided by shearing the metal at the ends of the slots 12, and bending the tongues of metal down thru the slots 12^a and clenching them beneath the upwardly offset portions 13^b of the metal-plate 13.

The inner, or slot-guard plate 13 is equipped with a pair of spring-wire slot-guards 14 for each of the coin-slots. Each 130

slot-guard 14 is in the form of a U-shape piece of spring wire having an anchor-arm 14^a and a free arm 14^b, whose extremity is bent to provide an oblique tongue 14^c which 5 extends across the coin-slot.

An anchorage 15 is provided for the loop portion of each bent wire guard by striking the metal of the plate 13 upwardly at points 15^a as will be understood from Figs. 10 and 10 12. The metal of the plate 13 is also struck upwardly at points 15^b to provide bearings or stops against which the free ends of the anchor-arms 14^a bear. The members of the 15 pair of slot-guards corresponding with each coin-slot are reversed in position, as will be understood from Fig. 10, and the spring tongues 14^c are separated from each other by a space so that the coin may be initially 20 partially entered between the spring tongues; and when the coin is forced in thru the coin-slot, the spring tongues will separate to admit the coin and then will spring back into the position shown in Fig. 25 10. It will be understood that the spring-wire slot-guards are housed between the slot-guard supporting-plate 13 and the top wall 5^b.

The rear edge of the slot-guard carrying-plate 13 is cut away as indicated at 16 in 30 Fig. 9 to admit the upper portion of the rear casing-section A² in such manner that the central portion of said plate may be embraced or caused to interlock with the pending flange or retainer 5^a of the casing-section A'. When this occurs, the retainer 5^a occupies the space 6 and is flush with the marginal flange 7 with which the casing-section A² is equipped at its rear side.

As will be understood from Figs. 6, 8, 17 40 and 22, there is provided below the flange or bottom wall 1^b of the coin-chamber a space which affords a bill chamber 18 into which bills may be inserted thru a bill-slot 18^a with which one lateral flange of the casing-section A' is provided. The bill chamber 18 also serves as a chamber for a locking device C.

The locking device C comprises a housing plate 19 which lies parallel with and is secured to the inner surface of the bottom flange 5^c of the casing-section A'; a reciprocal locking member or flat bolt 20 disposed between the housing member 19 and the bottom wall 5^c of the casing-section; a U-shape wire spring 21 confined between the bolt 20 and the bottom wall 5^c and having one end 21^a anchored to the housing member 19 and having the other end 21^b anchored to the bolt 20; and a key-barrel 22 extending thru the lower portion of the front wall 5 of the casing-section and having its inner end journaled in an upwardly extending projection 19^a with which the member 19 is equipped. The rear end of the key-barrel 60 projects some distance thru the bearing mem-

ber 19^a and is provided with a peripheral groove 22^a which is engaged by forwardly-struck lugs 19^b with which the member 19 is equipped, as will be understood from Fig. 20. A key 23 is adapted to enter the key-barrel. This key is provided with a bit 23^a which is adapted to engage a shoulder 20^a which is provided by punching a hole thru the bolt 20 which constitutes the bolt, as will be understood from Fig. 19. By 70 this means, the bolt may be retracted against the force of the spring 21. The bolt is provided at its rear edge with tongues or interlock flanges 20^b which serve to interlock with recesses 24 which are provided in the 75 lower portions of vertical ribs or flanges 24^a with which the plate A² is equipped on its inner side below the flange 1^d.

The housing plate 19 has its end portions struck downwardly to afford attaching 85 flanges 19^c which are secured to the bottom wall of the casing-section A' by means of rivets 25, as will be understood from Figs. 15 and 16. The housing member 19 of the locking mechanism is provided with downwardly struck lugs 19^d which afford guides 90 which are engaged by slots 20^e with which the plate-like bolt 20 is provided. This feature will be understood from Figs. 15, 16 and 21. 95

The rear casing-section A² is designed to fit within or be embraced by the marginal portions of the peripheral flange of the front casing-section. To facilitate the easy entry of the rear plate, the edge portions 100 thereof are beveled slightly, as indicated at 26 (Figs. 6, 17 and 22).

As has been indicated, when the casing-sections are locked together, the partial coin chambers 2 of the rear casing-section form, 105 with the partial coin chambers 2^a of the front casing-section, complete vertically disposed coin-chambers. The intermediate coin chambers are located between the complementary flanges with which the casing-sections are provided at their inner sides. The outer or marginal coin chambers are located between the corresponding complementary flanges and the lateral flanges 5^a of the casing-section A'. 110

The rear casing-section A² preferably is provided at its upper portion with a T-slot 27, as shown in Fig. 3. This enables the savings-bank to be hung on a nail or hook, if desired. Assuming the savings-bank to be in the upright position shown in Fig. 1, coins may be inserted thru the coin-slot 12, and the coins will drop to the bottoms of the coin-chambers and rest upon the inclined flange 1^d. The inclination of this flange 120 should be such as to give a slight tilt to the individual coins, but it should not be so great as to permit the coins to stand on edge or become jumbled. Also, the walls 125 of the coin-chambers which confine the coins 130

should permit the coins to drop freely into the coin chambers, but still should be sufficiently close or confining to prevent the coins from becoming jumbled.

It will be understood from the foregoing description that the improved savings-bank is adapted to receive the coins and maintain them in assorted, stacked relation, the coins of different denominations being contained in different coin chambers. It will be understood, also, that the savings-bank comprises a pair of open-faced complemental casing-sections provided with complemental partial coin chambers, so that when the casing-sections are brought together with their inner open faces the coin chambers will be completed. Furthermore, the rear casing-section or tray-section is adapted to maintain the coins in assorted columns when the front casing-section is removed, assuming the tray-section to be resting in the substantially horizontal position.

When the savings-bank is brought to a banking institution, the teller may lay it down upon a counter with the rear section bearing against the counter and may then unlock the front casing-section and remove it from the rear section, leaving the coins standing on edge in the tray-section, the coins being inclined at an angle corresponding with the inclination of the flange 1^a which constitutes the bottom walls of the coin chambers. The teller may then press the upper edge or column of coins towards the more sharply inclined surfaces, thus giving the coins a greater tilt or inclination and causing them to "fan out" more. He may then "tell off" the coins or count them rapidly, beginning at what corresponds with the upper edge of each column. In this operation, the coins will slide upon the surfaces 1^c which flank the longitudinal concavities 1^b.

If desired, the teller may grasp the rear or bottom end of the tray-section and withdraw the tray-section from beneath the coins, allowing the coins to "fan out" upon the counter in the manner shown in my Patent No. 1,170,525. He may then "tell off" or count the coins rapidly.

For the convenience of the teller, the stand or support B which is especially adapted to support the improved savings-bank has been devised. This may be employed, if desired. The stand B preferably comprises a square base 28, a standard 28^a, and a square top 28^b, the top being removably secured to the standard by means of screws 28^c. The top is provided with lateral flanges 28^d which are adapted to receive the savings-bank freely between them. The top is also provided inside the flanges 28^d with ribs 28^e which are separated from the flanges by spaces 28^f. The ribs 28^e are adapted to be embraced by the marginal

flange 7 of the tray-section, as will be understood by comparison of Figs. 22 and 23. Thus, the ribs 28^e will serve to prevent the savings-bank from shifting its position on the top 28^b of the stand B. In the use of 70 the stand, the savings-bank is placed thereon in the position shown in Figs. 4, 5 and 7; the teller then unlocks the front casing-section and removes it; he then presses the upper edges of the columns of coins away 75 from him or against the more sharply inclined surfaces 4; and he then counts the coins which remain properly assorted, according to their denomination.

It is particularly desirable, where the 80 coins are to be counted from the tray-section, to provide the tray-section itself with comparatively shallow partial coin chambers, and to so form these partial coin chambers that they afford substantially flat-bottomed guides or runways thru which the coins may slide as they are "told off" or counted. This facilitates the counting operation. Moreover, this feature tends to prevent disarrangement of the columns of 90 coins or getting the coins of different denominations mixed. The surfaces 1^c which flank the longitudinal concavities 1^b serve to elevate a coin which lies flatwise somewhat above the bottom of the recess, so that the finger may engage the rear edge of the coin in the counting operation.

The improved savings-bank is simple in construction, may be manufactured at moderate cost, may readily be given a beautiful 100 finish, and presents an exceedingly neat and attractive appearance. Moreover, the shape of the device is such as to enable the savings-bank to be readily slipped into a pocket or into a shopping-bag when it is desired to 105 take the savings-bank to a banking institution for the purpose of depositing the contents.

The foregoing detailed description has 110 been given for clearness of understanding only and no unnecessary limitations should be understood therefrom, but the appended claims should be construed as broadly as permissible in view of the prior art.

What I regard as new, and desire to 115 secure by Letters Patent, is—

1. A savings-bank comprising a pair of substantially flat-sided complemental open-sided casing-sections having complemental partial coin chambers and forming when together a substantially flat body, coin-admission means for said coin chambers, and means for locking the sections together.

2. A savings-bank comprising a pair of complemental casing-sections having complemental partial coin chambers, one of said sections having relatively low division walls between the partial coin chambers thereof and being adapted to serve as a tray-section, coin-admission means for said coin cham- 130

bers, and means for locking the casing-sections together.

3. A savings-bank comprising a pair of complementary casing-sections having complementary partial coin chambers, one of said sections constituting a tray-section and having its inner surface provided with longitudinal recesses flanked by surfaces upon which the coins may slide during removal from the tray-section, coin-admission means for said coin chambers, and means for locking the casing-sections together.

4. A savings-bank comprising a pair of substantially flat-sided open-sided complementary casing-sections having complementary partial coin compartments with complementary division walls between the compartments and forming when together a substantially flat body, coin-admission means corresponding with the coin compartments, and key-controlled locking means securing the casing-sections together.

5. A savings-bank comprising a tray-section consisting of a plate and longitudinal division walls projecting from the inner side of said plate, a closure comprising a front wall provided with a peripheral flange adapted to engage the edges of said tray-section, said front wall being equipped with rearwardly projecting longitudinal division walls corresponding with the division walls of said tray-section, coin-admission means corresponding with the coin compartments, and locking means securing said sections together.

6. A savings-bank comprising a tray-section consisting of a plate equipped with intermediate longitudinal division walls, a cover-section comprising a front wall and a peripheral flange within the margin of which said tray-section is received, said cover-section being equipped interiorly with longitudinal division walls complementary to said first-named division walls, coin-admission means corresponding with the several coin-compartments, and key-controlled locking means serving to secure said sections together.

7. A savings-bank comprising an open-sided tray-section provided with longitudinal division walls and equipped near the lower end of the section with an inclined flange affording bottoms for coin compartments, an open-sided cover-section provided with a peripheral flange within which the peripheral portion of the tray-section fits, said cover-section being equipped internally with longitudinal division walls, coin-admission means at the upper end of said closure section, and means for locking said sections together detachably.

8. A savings-bank comprising an open-sided tray-section and an open-sided cover-section having a peripheral flange receiving the tray-section, said sections being provided

internally with complementary division walls which divide the interior of the savings-bank into coin compartments, the lateral portions of the peripheral flange of the cover-section serving as lateral walls for the outer coin compartments, coin-admission means associated with the top flange of the cover-section, and locking means securing said sections together.

9. A savings-bank comprising complementary casing-sections provided with complementary partial coin chambers, one of said sections being equipped with an inclined flange constituting bottoms for the coin chambers and the other section constituting a cover-section provided with a peripheral flange which embraces the peripheral portion of the first-mentioned section, coin-admission means associated with the top wall of said cover-section, and key-controlled locking means securing said sections together.

10. A savings-bank comprising a tray-section and a cover-section, said tray-section being provided with longitudinal division walls and with a wall constituting bottoms for coin compartments and said cover-section being provided with a peripheral flange and with longitudinal division walls complementary to said first-mentioned division walls, interlocking connections between the upper portions of said casing-sections, key-controlled locking means mounted in the lower portion of the cover-section and coacting with a locking member at the lower end of said tray-section, and coin admission means associated with the top flange of the cover-section.

11. A savings-bank comprising a tray-section provided with partial coin compartments separated by division walls, a flange near the bottom end of said tray-section constituting a bottom wall for the coin chambers, a cover-section provided with vertical division walls which are complementary with respect to said first-named division walls and provided also with a peripheral flange, the upper portions of said sections being provided with interlocking means which are brought into engagement when the tray-section is inserted in the cover-section, a locking device mounted in the lower end of the cover-section, and coin-admission slots at the top wall of the cover-section.

12. A savings-bank comprising a tray-section consisting of a substantially flat metal plate provided with longitudinal division walls and equipped near its lower end with a transverse flange which projects beyond said division walls and affords bottoms for coin compartments, a cover-section comprising a bowed front wall and a peripheral flange which embraces the peripheral portion of the tray-section, said

bowed front wall being equipped with rearwardly projecting division walls complementary with respect to said first-mentioned division walls, the top wall of the cover-section being equipped with coin-admission means corresponding with the several coin compartments, and key-controlled locking means securing said sections together.

13. A savings-bank comprising a tray-section consisting of a substantially flat metal plate equipped with relatively low longitudinal flanges constituting division walls, said plate having its inner surface provided with longitudinal concavities flanked by longitudinal flat surfaces, a relatively high inclined flange projecting from said plate and constituting bottom walls for coin compartments, a cover-section comprising a bowed front wall equipped with a peripheral flange embracing the peripheral portion of the tray-section and equipped with intermediate flanges complementary with respect to said first-named flanges, the lateral portions of the peripheral flange of the cover-section constituting lateral walls for the outer coin compartments, coin-admission means including coin-slots extending thru the top wall of the cover-section, and key-controlled locking means securing said sections together.

14. A savings-bank comprising complementary open-faced casing-sections provided with complementary partial coin compartments separated from each other by complementary division walls, one of said casing-sections constituting a tray-section and having near its lower end an inclined flange constituting bottom walls for the coin compartments, said flange forming an angle of less than 20° with respect to a horizontal plane, coin-admission means corresponding with the several coin compartments, and locking means securing said casing-sections together.

15. In a savings-bank, an open-sided tray-section comprising a plate and relatively low longitudinal division walls, and an inclined flange near one end of said plate which projects beyond said division walls and is adapted to form the bottoms of coin compartments when the tray-section is in use in connection with a complementary casing-section.

16. In a savings-bank, a tray-section adapted to form one wall of a savings-bank, said tray-section having its inner side equipped with relatively low longitudinal walls affording partial coin compartments, and inclined walls at the bottom ends of said partial compartments and projecting beyond said division walls and adapted to serve as bottoms for the coin compartments when the tray-section is in use in connection with a companion casing-section.

17. A savings-bank comprising a tray-section consisting of a substantially flat plate equipped on one side with longitudinal division walls and with a transverse inclined wall which projects beyond said division walls, said transverse wall having its marginal portion cut away on a plane to afford a steeper incline than is afforded by the main body of the transverse inclined wall.

18. In a savings-bank, the combination of a tray-section consisting of a flat plate having its inner side equipped with longitudinal division walls, inclined bottom walls at the lower ends of said division walls and projecting beyond the same, the inclination of said bottom walls being small with respect to a horizontal plane and the margins of said bottom walls being cut away on inclined planes of greater inclination, a cover-section provided with a marginal flange adapted to embrace the marginal portion of said plate and provided with intermediate division walls complementary with respect to said first-mentioned division walls, coin-admission means at the top of said cover-section, and locking means connecting said sections together.

19. A savings-bank comprising a tray-section consisting of a substantially flat metal plate provided on one side with longitudinal partial coin compartments and with a flange projecting beyond the division walls of said partial compartments and affording bottoms for the coin compartments, a metal cover-section comprising a front wall and a marginal wall, sheet-metal division walls secured to the inner surface of the front wall of said cover-section, coin-admission means at the upper end of said cover-section, and locking means securing said sections together.

20. A savings-bank comprising a cover-section consisting of a front wall and top, bottom and lateral marginal walls, said top marginal wall being provided with coin-slots, a slot-guard plate spaced inside of said top wall, slot-guards mounted on the upper surface of said plate and confined in the space between said plate and said top wall, said slot-guard plate having coin-slots registering with said first-named coin-slots, the rear edge portion of said slot-guard plate being cut away and the top wall of said cover-section being equipped at its free edge with a depending flange, a tray-section consisting of a substantially flat plate equipped with longitudinal division walls, the upper edge of said plate engaging the inner surface of said depending flange, and locking mechanism mounted in the lower portion of the cover-section and coacting with a locking member with which the lower end of the tray-section is equipped.

21. A savings-bank comprising a pair of

- complemental casing-sections provided with complemental vertical partial coin compartments, one of said casing-sections having a top wall provided with coin-slots, an inner 5 plate secured to and spaced with relation to said top wall and provided with registering coin slots, guard slots mounted on the upper surface of said inner plate and extending across said coin-slots, and locking 10 mechanism securing said sections together.
22. In a savings-bank, the combination with a wall provided with a coin-slot of an inner plate spaced with relation to said wall and provided with registering coin-slots, 15 and spring-wire slot-guards disposed between said plate and wall and having spring members extending across the coin slots.
23. In a savings-bank, the combination with a wall provided with a coin-slot, of an inner plate spaced with relation to said wall and provided with a registering coin-slot, and a U-shape spring-wire slot-guard mounted between said inner plate and said wall and having a spring tongue extending 25 across the coin-slot.
24. In a savings-bank, the combination with a wall provided with a coin-slot, of an inner plate provided with a registering coin-slot, and a pair of spring-wire slot-guards 30 associated with said coin-slot and mounted between said inner plate and said wall, the slot-guards having opposed spring tongues extending across the coin-slots and separated by a space so that when a coin is 35 inserted the spring tongues will be spread apart to admit the coin.
25. In a savings-bank, the combination of an outer wall provided with coin-slots, of an inner slot-guard plate provided with registering coin-slots, and spring-wire slot-guards mounted on said inner plate and having yielding members extending across the coin-slots.
26. A savings-bank comprising an open 45 sided tray-section and an open-sided cover-section, the cover-section having lateral flanges and top and bottom flanges, the top flange being provided with coin-slots, and having clenching lugs formed at the ends thereof, an inner slot-guard plate provided with coin-slots registering with said first-named slots, said clenching lugs extending thru the ends of the coin-slots of the inner 50 plate and being clenched beneath the inner plate, slot-guards mounted on the upper side of said inner plate, and locking mechanism connecting said sections together.
27. A savings-bank comprising an open-sided tray-section and an open-sided cover-section which are complemental with respect to each other, the cover-section having lateral flanges and top and bottom flanges, the top flanges being provided with an interlocking shoulder which engages and over- 55 lies the upper marginal portion of the tray-section, coin-admission means associated with the top flange of the cover-section, and locking mechanism mounted on the upper surface of the bottom flange of the cover-section and serving to engage a locking shoulder with which the lower end of the tray-section is equipped.
28. A savings-bank comprising an open-sided tray-section and an open-sided cover-section which are complemental with respect to each other, the cover-section having lateral flanges and top and bottom flanges, the top flange being provided with an interlocking shoulder which engages and overlies the upper marginal portion of the tray-section, coin-admission means associated with the top flange of the cover-section, and locking mechanism mounted on the bottom flange of the cover-section comprising a housing member secured to said bottom flange, a plate-like bolt confined between said housing member and said bottom flange and equipped with a rearwardly projecting interlocking member adapted to engage a recess with which the lower end of the tray-section is provided, and a spring tending to hold said plate in the locked position.
29. A savings-bank comprising an open-sided tray-section and an open-sided cover-section, said cover-section being provided with top, lateral and bottom flanges, interlocking means between the free edge portion of the top flange and the upper end of the tray-section, coin-admission means associated with the top flange of the cover-section, and locking mechanism mounted on the bottom flange of the cover-section, said locking mechanism comprising a bolt sliding parallel with the bottom flange, and a key-barrel extending thru the lower portion of the front wall of the cover-section.
30. A savings-bank comprising a pair of complemental casing-sections provided with open-sided complemental partial coin-chambers, one of said sections constituting a tray-section and the other constituting a cover-section, the cover-section being provided with top, lateral and bottom flanges, interlocking means between the upper portion of the tray-section and the upper portion of the cover-section, and locking mechanism mounted on the bottom flange of the cover-section, comprising a housing member secured to said bottom flange, a plate-like bolt confined between said housing member and said bottom flange, and a wire spring having one end connected with said housing member and having the other end connected with said bolt.
31. In means of the character set forth, the combination of a stand, and a savings-bank comprising an open-sided tray-section and an open-sided cover-section, and lock-

ing mechanism securing said sections together, said tray-section and the top of said stand being provided with means for preventing shifting of the tray-section when it rests on said stand.

32. A savings-bank comprising an open-sided tray-section and an open-sided cover-section which are provided with complementary partial coin-compartments, locking

mechanism securing said sections together, **10** the tray-section being provided at its outer side with a marginal flange; and, in combination therewith, a supporting stand having a top equipped with flanges adapted to interlock with the marginal flange of the **15** tray-section when the tray-section rests upon said stand.

CHARLES FISHER.
